UNITED STATES PATENT OFFICE.

STEPHEN S. HORN, OF BROOKLYN, NEW YORK.

THEATRICAL SCENERY.

Application filed March 29, 1921. Serial No. 456,588.

To all whom it may concern:

Be it known that I, STEPHEN S. HORN, a citizen of the United States, and resident of Brooklyn, in the county of Kings and State 5 of New York, have invented certain new and useful Improvements in Theatrical Scenery, of which the following is a specification.

The present invention relates to improvements in theatrical scenery of the multiplex type or that type wherein the same set of scenery may be manipulated and used to simulate different interiors, exteriors, or a combination of these and the like.

15 The general object of the invention is to adapt a set of multiplex scenery so that the same may be set up or struck with a minimum number of stage hands thereby effecting an economy in point of stage labor and 20 this without involving an increase in the time element of striking or setting up, the structure being such that the operation of changing from one scene to another may be effected in a comparatively short interval.

25 Another object is the provision of a multiplex set of scenery which may be adapted to provide for any desired number of scenes in that the complete setting up of one scene is 30 permitted out of view from the audience while another scene is displayed.

To these ends the invention resides in turnable frames for supporting the wing sections, the said frames being constructed 35 with a plurality of supporting surfaces each of which is adapted to support any desired piece of scenery and to display the same when turned into a predetermined relation to the stage platform, each of said 40 supporting surfaces to be so constructed and arranged as to appear successively in view of the audience and thus display the scenery supported thereby when the wing pieces are turned. The said wing pieces are further 45 constructed so as to combine with a pivoted ceiling piece arranged so as to swing vertically and cooperating with wing pieces and thereby constitute a scenery ceiling.

Other objects will appear and be better understood in that embodiment of the inven-

tion in which the following is a specification reference being had to the accompanying drawings forming a part thereof in which—

Figure 1 is a front elevation of that stage showing the proscenium arch and my invention in use. 55

Figure 2 is a plan view of the set in set up or operative position.

Figure 3 is a detail vertical cross section showing the area between the back of the 60 stage and the proscenium arch, and at approximately the middle portion of the stage and indicating the appearance of the parts when viewed from the wings or off stage.

Figure 4 is a view at right angles to Figure 1 with the wings and ceiling removed and showing the structure of stage platform having incorporated therewith a water tank. 65

Figure 5 is a detail side elevation of one of the cranes or ceiling supports. 70

Figure 6 is an enlarged detail section in plan of one of the corner portions of the wing pieces.

Figure 7 is a detail side elevation of the upper mounting of one of the wing pieces. 75

With reference to Figures 1 and 3, 5 indicates a proscenium arch and 6 the back of the stage the platform of which is indicated generally by a. The usual divisions of the stage into upper, lower and intermediate side entrances are located between the back 6 and the sides of the proscenium arch 5 and in alignment with the sides of the said arch. In that various scene plots may require the use of any or all of these entrances 80 and in some cases eliminate the use of entrances entirely, it would serve no useful purpose to illustrate and describe the device of this invention in connection with the various scene plots that could be proposed. 85 Therefore, the description will now proceed to set forth an embodiment which may be used for simple interiors, exteriors, and combinations of these or the like, it being obvious that where effects in accordance with 90 other scene plots are required, these may be had simply by changes in form, degree, and arrangement or disposition of the element to be described. 95

In Figures 1 and 2 the opposite sides of 100

the stage are flanked by the wing pieces 8 and 9 which extend from the tormentors (not shown) to the center piece 10 located in the back or upper part of the stage and cooperating therewith to give the effect of the interior of a room in a dwelling or the like. The wing pieces 8 and 9 may be ordinary pieces of canvas suitably decorated and adapted to be connected to frames 11 and 12 which may be of any desired construction. The frames 11 and 12 are joined on one side to frames 13 and 14 herein shown as corresponding in point of size and structure to the frames 11 and 12 and disposed in angular relation thereto. The frames 12 and 13 are further connected to frames 15 and 16 which may be constructed to correspond with the frames 11, 12, 13 and 14 or be made up of sections arranged in angular relation to each other as shown in Figure 2 and for a purpose hereinafter to be described. The frames 15 and 16 are disposed in angular relation to the frames 11, 12, 13 and 14 and cooperate therewith to provide triangular shaped supports, the corner portions of which are connected to suitable braces 17 which serve to straighten the frames as shown in Figures 2 and 6. The braces 17 are located at the upper and intermediate portions of the supports and are arranged so as to intersect on approximately the central line of the supports and at these points suitable structures are provided for securing the opposite end portions of vertically disposed shafts 18 and 19 which are fixedly secured to the supports through braces 17 and terminate in trunnions indicated by 19' in Figure 7 which trunnions are journaled in bearings, one of which is shown in Figure 7 and indicated by 20. The lower bearings (not shown) being secured to the stage platform and the upper carried by brackets 21 secured to any suitable support as, for instance, the side and front walls of the stage.

Referring to Figures 2, 3 and 5 a pair of cranes are disposed on opposite sides of the stage and in the region of the upper entrances thereof. The masts 22 and 23 of these cranes may be of any suitable structure and at their lower ends are suitably connected to the stage platform. The arms 24 and 25 are pivoted to the upper ends of the masts 22 and 23 and are so constructed and arranged as to swing vertically on the masts. As shown in Figures 3 and 5 that end of each arm adjacent to the back 6 of the stage is provided with a quadrant 26 or other suitable equivalent for supporting a flexible cable 27 which is connected at one end to the arm and at its opposite end carries a weight 29 which serves as a counter balance for the arm. In the structure illustrated in Figures 1, 2 and 3 the arms 24 and 25 serve as supports for a piece of scenery representative of a ceiling. In this connection it will

be observed that the masts 22 and 23 are of such height as to adapt the arms 24 and 25 to support the ceiling piece 30 so that the same will be supported in proper relation to the upper ends of the wing pieces by the weights 29 when the arms are in horizontal position and thereby adapt the ceiling piece 30 to cooperate with the wing pieces 8 and 9 and center piece 10 to give the full effect of the interior of a dwelling or of the like. It will be understood that the ceiling piece 30 which may be a piece of suitable decorated canvas or the like may be secured to the arms 24 and 25 in any desired manner.

The stage platform *a* of the present invention is shown in Figures 1 and 4 inclusive as having combined therewith a tank 31, this tank is located below the surface of the platform *a*, and normally covered by two sections 32 and 33 thereof as shown in Figure 4. The sections 32 and 33 are made up of a plurality of hingedly united boards or strips and each section has connected thereto the ends of a cable 34 which is trained upwardly over pulleys 35 and then downwardly and under the stage platform as shown in Figures 3 and 4, the structure being such that when the outwardly or downwardly extending runs of the cable are pulled the sections 32 and 33 will be moved from the positions shown by dotted lines in Figure 4 to that shown by full lines and thereby expose the tank 31 through the platform *a*. As shown in Figures 3 and 4 suitable counter weights 36 are provided for counterbalancing the weights of the sections 32 and 33 when these are in the full line position as shown in Figure 4.

From the foregoing it will be observed that with the use of this invention the operation of changing from one scene to another may be effected in a manner that will practically eliminate any relatively appreciable amount of intermission in that when the parts are positioned as shown in Figures 1 and 2 the operation of changing or striking the scene may be accomplished simply by turning the supports so that the frames 11 and 12 will move to the position occupied by the frames 15 and 16 in which event the frames 13 and 14 will be arranged so as to be in view of the audience. In effecting a change in the wing pieces as just described a change may also be effected if desired in the ceiling piece. This can be accomplished by securing two ceiling pieces to the arms 24 and 25 by arranging the ceiling pieces one upon the other so that in order to effect the change in the ceiling pieces it will be necessary only to detach the outer ceiling piece which would be accomplished after the lowering of the arms 24 and 25. In connection with the lowering of the arms 24 and 25 the frames 15 and 16 would be turned to the positions indicated by dotted

lines in Figure 2 and in turning to these positions sufficient clearance would be provided for the downward movement of the arms 24 and 25 by reason of the angularity 5 of the frames 15 and 16 which are shown by dotted lines in Figure 2. It is also to be observed that many attractive effects may be obtained by the use of the arms 24 and 25 in that these arms may serve to support 10 on their upper sides, as viewed in Figure 3, structures representative of a water fall so that when the arms are lowered to the position shown in Figure 5 and the tank 31 uncovered by the sections 32 and 33 water 15 caused to flow downwardly and over the structure supported by the arms will be directed into the tank 31. It is to be observed that in the operation of setting up and 20 striking scenery constructed in accordance with this invention a change in scenery may be effected by comparatively few stage hands and the device moreover permits carrying out of an infinitely large number of changes on relatively small stages, where 25 hitherto only comparatively few changes could be made on account of inadequate space involving the use of many pieces of scenery. It is to be further observed that when the cranes and frames are set up as 30 shown there is practically no limit to the number of different scenery changes that may be made with these structures. This is especially true of the frames as evidenced in a case where it may be supposed that the 35 frames 13 and 14 have just been moved from the positions shown as being occupied by the frames 11 and 12 in Figures 1 and 2. In this connection the scenery on the frames 13 and 14 can be readily removed and other 40 required scenery arranged on the said frames ready for use in the event that a third change is required during the progress of an act, all of which may be done in a rapid and expeditious manner. It will be observed 45 by reference to Figure 3 that a space indicated by 38 is provided between the masts 22 and 23 and the frames. This space is provided for the reception of the backing or center piece 10 and its presence admits of 50 the ready withdrawal or insertion of such backing or center piece or the equivalent thereof.

Thus it will be seen that the device of the present invention overcomes many disadvantageous features heretofore found in the construction of stage scenery in that the setting up and striking has required considerable time and the employment of a relatively large amount of labor and the use of 60 which also required considerable stage floor space.

It is obvious that those skilled in the art may vary the details of construction and arrangement of parts without departing 65 from the spirit of my invention, and, there-

fore, I do not wish to be limited to such features except as may be required by the claims.

What I claim is:—

1. A theatrical stage platform having arranged thereon a plurality of rotatable scenery carrying supports and a pivoted ceiling piece constructed and disposed so as to cooperate with said supports to constitute a 70 scenery ceiling. 75

2. A theatrical stage platform having arranged thereon a plurality of rotatable scenery carrying supports and a pivoted and counter-balanced ceiling piece constructed and disposed so as to cooperate with said 80 supports to constitute a scenery ceiling. 85

3. A theatrical stage platform having arranged thereon and in the wings thereof a plurality of oppositely disposed scenery carrying supports, a crane disposed between said 85 supports and having an arm arranged for vertically swinging movement, said arm being adapted for connection to a piece of scenery and constructed and disposed so as to support the same at an incline to the said 90 supports or parallel with the upper end portions thereof. 95

4. A theatrical stage platform having arranged thereon and in the wings thereof, a plurality of oppositely disposed scenery carrying supports, a crane disposed between said supports and having a counterbalanced arm arranged for vertically swinging movement, said arm being adapted for connection to a piece of scenery and constructed and disposed so as to support the same at an incline to the said supports or parallel with the upper end portions thereof. 100

5. A theatrical stage platform having a tank in the front or outer portion thereof, a crane having an arm arranged for vertically swinging movement and adapted to be connected to a piece of scenery, said arm being constructed and disposed so as to support the scenery carried thereby so that the 105 same will incline upwardly from the said tank. 110

6. A theatrical stage platform having a tank in the front or outer portion thereof, a crane having a counter-balanced arm arranged for vertically swinging movement and adapted to be connected to a piece of scenery, said arm being constructed and disposed so as to support the scenery carried thereby so that the same will incline upwardly from the said tank. 115 120

7. A theatrical stage platform having arranged thereon and at the back portion thereof cranes consisting of oppositely disposed masts and vertically swinging arms 125 connected to the said masts, said cranes being disposed in opposite wing portions of the stage and the arms thereof being adapted for supporting a piece of scenery, a pair of rotatable supports disposed between the 130

cranes and the front of the stage and located in opposite wing portions thereof, said cranes being so constructed as to enable the arms thereof to support the scenery carried thereby substantially parallel with the upper end portions of the support when the arms are in horizontal position, and said supports including each in its structure a plurality of

angularly disposed frames, each of which is adapted to be connected to a piece of scenery and support the same.

Signed at New York, in the county of New York and State of New York, this 24th day of March, A. D. 1921.

STEPHEN S. HORN.
